CLAIM

The ornamental design for a golf club face, as shown and described.

DESCRIPTION

FIG. 1 is a front plan view of the golf club face; FIG. 2 is an enlarged view of the highlighted region of FIG. 1;

FIG. 3 is a cross-sectional view of the embodiment shown in FIG. 2 along lines 3-3; and,

FIG. 4 is a cross-sectional view of the embodiment shown in FIG. 2 along lines 4-4.

The broken lines in the figures show portions of the golf club face that form no part of the claimed design.
